[57] CLAIM

The ornamental design for a counter-weighted pet toy,
as shown and described.

DESCRIPTION

FIG. 1 is a front elevational view of a counter-weighted
pet toy showing my new design;
FIG. 2 is a top plan view thereof;
FIG. 3 is a bottom plan view thereof;
FIG. 4 is a left side elevational view thereof;
FIG. 5 is a right side elevational view thereof;
FIG. 6 is a rear elevational view thereof; and
FIG. 7 is a perspective view thereof.
